UNITED STATES PATENT OFFICE

MAXIMILIAN C. MEYER, OF BROOKLYN, NEW YORK, ASSIGNOR TO JOSEPH H. MEYER
BROTHERS, OF BROOKLYN, NEW YORK, A CORPORATION OF NEW YORK

ARTICLE OF MANUFACTURE

Application filed January 29, 1930. Serial No. 424,173.

This invention relates in general to jewelry articles, particularly to a tip to be employed on strung necklaces and to provide means for attaching the clasp thereto.

5 One of the objects of this invention is to provide a tip of this nature which is exceedingly simple in structure and adapted to cheap and rapid manufacture.

Another object of this invention is the provision of a tip which may be attached to the string or wire portion of the necklace by forming a knot therein and threading the string or wire through a hole in the tip so that the knot lies in the thimble or cup portion of the tip.

A still further object of this invention is the provision of an integral hook which may be attached to the clasp and closed to permanently secure the clasp thereto.

20 These and other objects as will appear from the following description are secured by means of this invention.

This invention resides substantially in the combination, construction, arrangement and 25 relative location of parts, all as will appear more fully hereinafter.

Referring to the drawings—

Figure 1 is a side elevational view of the tip of this invention;

30 Fig. 2 is a cross sectional view taken in line 2—2 of Fig. 1;

Fig. 3 is a vertical cross sectional view taken on the line 3—3 of Fig. 2; and

35 Fig. 4 is a side elevational view of a string of beads, for example with the tips of this invention attached at each end.

Some difficulty is encountered in providing means by which the clasp of a necklace may be readily attached thereto in a permanent 40 manner. The general purpose of this invention is to provide a small tip which can be readily attached to the string or wire of the necklace, and which provides an easily closable hook to which the clasp can be attached.

45 The invention will be more readily understood by referring to the drawings.

The tip is shown comprising a small hollow thimble like tip portion 1, having an integral hook 2 attached to the body portion on 50 one side and free at the other, so that the

hook can be forced down to make a closed link. The bottom of the tip portion is provided with a small central hole 3. In use the necklace string 4 is provided with a knot 5 at each end which lies within the body portion 1 of the tip. The string 4 of course passes through the holes in the bottom of the body portion and the knot holds the tips firmly in place with the beads or other ornaments between them. The clasps, as is well known, are made in two parts. One part would be hooked on to the hook of one tip and the other part on to the hook of the other tip and both hooks closed, permanently attaching the clasp parts to the necklace. 65

In view of the foregoing disclosure it will be apparent that the device of this invention may be readily changed by those skilled in the art, without departing from the principle and scope of this invention, and I do not, therefore, desire to be strictly limited to the disclosure as given for purposes of illustration, but rather to the spirit and scope of the appended claims. 70

What I seek to secure by United States Letters Patent is:

1. In a necklace tip of the type described the combination comprising a thimble portion and a closable hook portion integrally united, said thimble portion having an aperture therethrough. 80

2. In a construction of the type described the combination comprising two tips having apertured hollow body portions and closable hooks thereon, and a string to receive ornaments extending through said apertures and knotted at the ends. 85

3. In the combination as described a string to receive ornaments, tips therefor having apertured hollow body portions, and integral closable hook members on the body portion the ends of said string passing through said apertures and being knotted, said knots lying within the hollow body portion. 90

In testimony whereof I have hereunto set my hand on this 27th day of January A. D. 1930.

MAXIMILIAN C. MEYER.
